(57) **CLAIM**

The ornamental design for a portable multi position magnifier camera, as shown and described.

DESCRIPTION

FIG. 1 is a front elevational view of a portable multiple position magnifier camera of the present invention shown in the reading orientation;

FIG. 2 is a rear elevational view of the portable multi position magnifier camera of the present invention in the reading orientation;

FIG. 3 is a left hand side elevational view of the portable multi position magnifier camera of the present invention in the reading orientation;

FIG. 4 is a right hand side elevation view of the portable multi position magnifier camera of the present invention in the reading orientation;

FIG. 5 is a top plan view of the portable multi position magnifier camera of the present invention in the reading orientation;

FIG. 6 is a bottom plan view of the portable multi position magnifier camera of the present invention in the reading orientation;

FIG. 7 is a perspective view of the portable multi position magnifier camera of the present invention in the reading orientation;

FIG. 8 is a perspective view of the portable multi position magnifier camera of the present invention in a closed orientation;

FIG. 9 is a perspective view of the portable multi position magnifier camera of the present invention in a writing configuration; and,

FIG. 10 is a perspective view of the portable multi position magnifier camera of the present invention in a hand held configuration.
